LOCKING COUPLER

John J. Funk, Chicago, Ill.

Application January 27, 1953, Serial No. 333,571

6 Claims. (Cl. 284—17)

1

This invention relates to a coupling device for establishing communications through a conduit, and more particularly, couplers wherein a nozzle is inserted in a socket member and the nozzle itself opens a baffle in the socket member.

The primary object of the invention is to provide an improved coupling device wherein the socket member can only be opened by a specially designed and fitted nozzle. This prevents accidental connections wherein only one particular type or grade of liquid is to be admitted into a conduit to a tank or the like. The coupling has varied uses such as the supply line to a gasoline tank of a service station, the supply lines to tanks of ink in printing establishments, connections to chemical storage tanks and the like.

A further object of the invention is to provide a coupling device wherein the nozzle itself serves as a key which may be inserted into the socket member and turned to open a shutter or baffle in the socket member, and then inserted further and locked in connected position.

Another object of the invention is to provide a locking device for the baffle which is automatically unlocked by the nozzle before it moves the baffle from closed position.

Still another object of the invention is to provide a valve in the nozzle member which is automatically opened when the nozzle is fully inserted into the socket member.

The invention is illustrated in a preferred embodiment in the accompanying drawings, in which—

Fig. 1 is a vertical sectional view of a nozzle member which serves with the socket member to provide a locking coupling;

Fig. 2 is a top plan view of the socket member;

Fig. 3 is a fragmentary plan view, showing the baffle in locked position;

Fig. 4 is a fragmentary vertical sectional view, taken as indicated at line 4—4 of Fig. 2;

Fig. 5 is a view similar to Fig. 4, taken as indicated at line 5—5 of Fig. 9, but showing the coupling in connected open position;

Fig. 6 is a fragmentary elevational view showing the lower end of the nozzle locked to the socket member;

Fig. 7 is a fragmentary sectional view showing the nozzle fully inserted but before being turned to the locked position shown in Fig. 6;

Fig. 8 is a view similar to Fig. 7, but taken in locked position, as indicated at line 8—8 of Fig. 5;

Fig. 9 is a plan sectional view, taken as indicated at line 9—9 of Fig. 5;

2

Fig. 10 is a plan sectional view, taken as indicated at line 10—10 of Fig. 5, showing the nozzle fully inserted and the baffle turned to open position;

Fig. 11 is a fragmentary plan sectional view, taken as indicated at line 11—11 of Fig. 4; and

Fig. 12 is a fragmentary plan sectional view, taken as indicated at line 12—12 of Fig. 4.

In the embodiment illustrated, the nozzle member shown in Fig. 1 has a cylindrical tube 14 provided with a lateral opening 14a which is normally closed by a tubular sleeve 15. The sleeve 15 is urged to closed position by a compression spring 16 provided in a crown member 17 which has a laterally extending tubular arm 18 in alignment with the opening 14a. A flexible hose, not shown, may be connected to the arm 18. The sleeve member 15 is shown provided with a slot 19 engaged by a set screw 20, so as to limit its travel in the tube 14. The lower end of the tube 14 is shown provided with an outwardly extending lug 21, which, if desired, may be notched like an ordinary key so as to fit certain socket members.

The socket member comprises a main frame 22, which in the embodiment illustrated has an upper and lower plate held in spaced relation by means of screws 23. A sleeve portion 24 is secured by screws 25 to a bridge-like member 26 which is bolted to the upper plate of the main frame 22 by means of screws 27. The sleeve member has an opening of the same diameter as the outer diameter of the nozzle tube 14 and has a slot 28 to admit the lug 21.

A rotary sleeve 29 is journaled in the upper plate of the frame member 22, and has an opening in alignment with the opening in the fixed sleeve portion 24. The rotary sleeve 29 has a slot 30 to receive the lug 21 on the nozzle, and is in alignment with the slot 28 when the device is in the locked position shown in Fig. 4.

The lower plate of the frame 22 is provided with a lower fixed sleeve portion 31 which is fixed in position by machine screws 32. This lower fixed sleeve 31 also has a slot 31a to receive the nozzle lug 21 and connects with a lateral slot 33, so that when the nozzle is fully inserted in the socket member, it may be turned from the position shown in Fig. 7 to that of Figs. 5, 6 and 8, and the lug 21 will hold the nozzle down in that position.

As best shown in Fig. 4, the member 31 is provided with a fixed, upwardly extending sleeve 34 which is spaced from the inner wall of the member 31 and is adapted to extend up into the sleeve 14 of the nozzle member and push the sleeve valve

3

15 up into the position shown in Fig. 5 to open communication through the nozzle member.

In order that the socket member will automatically be closed and locked whenever the nozzle is detached, a baffle member 35 is fixed to a shaft 36 by means of collar members 37.

The shaft 36 is journaled in the plates of the frame 22 and is provided at its upper end with a mutilated operating gear 38. The rotary sleeve 29 is also provided with a mutilated gear having teeth to engage the teeth on the gear 38 and turn the baffle member 35 from its closed position shown in Fig. 3 to its open position shown in Fig. 10.

The frame 22 has a stop member 39 which limits the oscillation of the rotary sleeve 29 by engagement with teeth 40 and 41, as shown in Fig. 9.

In order to prevent the baffle 35 from being opened by anything but the proper fitting nozzle member, a special locking device is provided. As best shown in Fig. 10, one end of the baffle 35 is provided with a notch 42 which is adapted to be engaged by a bolt 43 slidably mounted in a guide member 44 secured to the frame 22 by means of machine screws 45. A ring 46 is secured to the under side of the upper plate of the frame 22 by means of screws 47 and this plate also has a notch 48 to receive the end of the bolt 43 when it is thrown to locked position. The plate also has a notch 48a which is in alignment with the slot in the lower sleeve member 31 so that after the nozzle has turned the baffle 35 to open position, it will be aligned for full insertion into the socket member.

The bolt 43 is operated automatically by the rotary sleeve 29. A pivot stud 49 extends upwardly through a slot 50 in the frame 22 and is connected to a stud 51 on the rotary sleeve by means of a link 52. The mutilated gears afford a lost-motion connection so that in the beginning of the movement, in a counterclockwise direction, as viewed in Fig. 2, the first action is to have the link 52 withdraw the bolt 43 from the slots 42 and 48, and then as the teeth on the mutilated gears come into contact, the baffle is thrown to the position shown in Fig. 10, against a stop 53. Movement in a counterclockwise direction, to close the baffle, is limited by the baffle engaging the stop 54, as shown in Fig. 3. Of course, when the rotary sleeve is turned in a clockwise direction from the position shown in Fig. 9, the bolt 43 is moved outwardly and then back into the locking position shown in Fig. 4.

Operation

In using the device, the sleeve of the nozzle member 14 is inserted in the fixed upper sleeve member 24 of the socket and the lug 21 travels downwardly through the aligned slots to the position shown in Fig. 4. The nozzle is then rotated in a counterclockwise direction until stopped by the tooth 40 engaging the stop 39. In this movement the bolt 43 is first withdrawn and then the baffle is turned to the position shown in Fig. 10. This movement will bring the lug into alignment with the slot provided in the lower fixed sleeve portion, and as the nozzle is pressed downwardly, the sleeve 15 in the nozzle will slide upwardly and open communication through the nozzle and socket member. The nozzle may then be given a slight clockwise movement which will cause the nozzle to be locked in the position shown in Fig. 5.

4

To withdraw the nozzle, the first counterclockwise movement moves the lug 21 to a position where it may be withdrawn upwardly until the lug is in the rotary sleeve. A clockwise rotation will then send the baffle to closed position, throw the bolt into locking position, and align the lug with the slot in the upper fixed sleeve member so that the nozzle may be withdrawn and the openings in both the nozzle and socket member will automatically be closed.

It will be understood that the device may be modified in a number of ways without departing from the spirit of the invention. The locking device and baffle may be operated by cams rather than mutilated gears and links, and castings can be used for the frame and fixed sleeve members. The foregoing detailed description is given for clearness of understanding only, and no unnecessary limitations should be understood therefrom, for some modifications will be obvious to those skilled in the art.

I claim:

1. A coupling device for establishing communication through a conduit, comprising: a cylindrical nozzle adapted to be secured to a flexible hose line, said nozzle being provided near its free end with an outwardly extending lug; and a socket member having an upper fixed sleeve portion with a slot to receive the end of said nozzle, a rotary sleeve having a slotted opening beneath and in alignment with said fixed sleeve portion, a movable baffle beneath and forming a closure for said rotary sleeve portion, means on the rotary sleeve for moving the baffle from closed position when said sleeve is turned by the nozzle, and a lower fixed sleeve portion with a slot to receive the end of said nozzle when the nozzle has been turned to open the baffle.

2. A coupling device as specified in claim 1, in which the lower fixed sleeve portion has a lug receiving opening communicating with its slot to hold the nozzle in connected position.

3. A coupling device as specified in claim 1, in which a sliding bolt is provided to lock the baffle in closed position, and an operating connection is provided between the rotary sleeve and bolt for withdrawing the bolt upon rotation of the sleeve before moving the baffle.

4. A coupling device as specified in claim 1, in which the baffle is pivotally mounted, a sliding bolt is provided to lock the baffle in closed position, a link connects the bolt to the rotary sleeve, and a lost-motion connection is provided between said sleeve and baffle for automatically withdrawing the bolt before turning the baffle.

5. A device as specified in claim 4, in which stops are provided on the rotary sleeve to limit its oscillation in both directions.

6. A coupling device as specified in claim 1, in which the nozzle has a lateral opening, a slideable sleeve closure is provided in said nozzle controlling communication through said opening, a spring is provided for urging said slideable sleeve to closed position, and an upwardly extending member is provided in the lower sleeve portion of the socket member to engage and open the slideable sleeve when the nozzle is fully inserted into said socket member.

JOHN J. FUNK.
